UNITED STATES PATENT OFFICE.

EDGAR H. CLARK, OF RICHMOND HILL, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

Application filed September 18, 1923. Serial No. 663,333.

To all whom it may concern:

Be it known that I, EDGAR H. CLARK, a citizen of the United States of America, residing at Richmond Hill, in the county of 5 Queens and State of New York, have invented certain new and useful Improvements in Telephone Systems, of which the following is a full, clear, concise, and exact description.

10 This invention relates to telephone systems and particularly to machine switching systems in which coordinate type switching mechanism is employed.

The object of the invention is to produce 15 a controlling arrangement which will be positive and accurate in its action.

A feature of the invention resides in the use of slow acting relays, the operation of which depends in such a manner upon the 20 voltage that the operating time interval may be held substantially constant for varying voltages, such variations as may occur being of a desirable character.

Heretofore in circuit arrangements such 25 as shown in the patent to S. B. Williams, No. 1,517,331, granted December 2, 1924, where it is necessary to cause a heavy current to flow to produce a certain result such as to operate a magnet and to thereafter reduce 30 the flow of such current, timing means such as a slow-releasing relay is depended upon to measure the interval. Due to the fact that a slow-releasing relay is energized for a comparatively long period prior to the opening 35 of its circuit, its core has had time to become fully saturated, the degree of saturation depending directly upon the voltage. To insure that the releasing time of the relay shall always be at least equal to a required 40 minimum, it is necessary to saturate the relay to a degree represented by a point out on the flat part of the well known magnetization curve. On this portion of the curve, a given increase in voltage corresponds to a 45 much greater time increment in the release of the relay than on the steep portion of the curve. Hence, for increasing voltages the time interval during which the heavy current flows is materially increased to the possible detriment of the apparatus.

In the present arrangement this difficulty is overcome by the use of slow-to-operate relays. The operating interval of these relays is more independent of voltage changes due 55 to the fact that their magnetization begins

at practically zero and is represented by the steep portion of the curve. It may be seen from the description of the circuits herein-after that since the interval is measured by the operating time of a relay and not by the 60 releasing time, if an increment of increase in voltage causes the timing relay to operate slightly faster, this fact will be advantageous. This is a desirable result since the increased voltage causes a quicker operation of 65 the heavy current magnets and therefore the time interval to provide for the completion of the operation of the magnet may be correspondingly short.

The invention is shown in a single sheet of 70 drawing comprising a diagrammatic illustration of the preferred form of circuit arrangement.

When the subscriber at substation 1 removes his receiver from its hook, line relay 75 2 becomes energized. Relay 4 thereupon operates over a circuit from ground, back contact and inner lefthand armature of relay 3, front contact and righthand armature of line relay 2, winding of relay 4 to grounded 80 battery. Relay 4 causes the energization of relay 3 through its inner right-hand armature and closes a circuit from ground, normal contacts of the armature of relay 5, armature and back contact of relay 6, outer 85 right-hand armature of relay 4, right-hand winding of relay 7 to battery and ground. Relay 7 attracts its armatures and closes, first a circuit for relay 8 through its outer right-hand armature, second, a holding circuit for 90 relay 3 through its inner right-hand armature, and third, a locking circuit for itself from ground, normal contacts of the armature of relay 5, winding of relay 6, inner left-hand armature and back contact of relay 9, inner left-hand armature and front contact of relay 7, left-hand winding of relay 7 to battery and ground. The energization of relay 3 opens the circuit of relay 4 so that this relay now becomes deenergized 95 but relays 3, 7 and 8 remain energized. In series with relay 7, relay 6 becomes energized and transfers the ground connection from its back contact to its front contact whereupon a circuit is established from 100 ground, the normal contacts of the armature of relay 5, armature and front contact of relay 6, left-hand armature and back contact of relay 10, outer left-hand armature and front contact of relay 7, outer left-hand 105 110

armature and front contact of relay 3, left-hand armature and front contact of relay 2, upper winding of relay 11 to battery and ground. Relay 11 becomes energized in this 5 circuit and closes a locking circuit through the winding of relay 10, the inner lower armature and front contact of relay 11, the lower winding of relay 11 to battery and ground. Relay 10 operates in this circuit. 10 Ground is now extended from the armature and front contact of relay 10 through the upper armature and front contact of relay 11 to vertical magnet 12 causing the energization of this magnet. At the same time, a 15 circuit is closed from ground, the armature and front contact of relay 10, through the lowermost armature and front contact of relay 11, the inner lower armature and back contact of relay 13, winding of vertical magnet 14 to battery and ground causing the 20 energization of this magnet. Upon the energization of magnets 12 and 14 a circuit is closed from ground, front contact and outer lower armature of magnet 14, conductor 15, outer lower armature and front contact of 25 magnet 12, conductor 16, winding of relay 17 to battery and ground. Simultaneously therewith a circuit is closed from ground through the front contact and outer lower armature of magnet 14, conductor 15, the 30 inner lower armature and front contact of magnet 12, conductor 18, front contact and innermost left-hand armature of relay 8, inner left-hand armature and back contact of relay 19, right-hand winding of horizontal magnet 20 to battery and ground. It will be noted that the two vertical magnets jointly 35 control the circuit for the energization of the horizontal magnet and that at the same time they close a circuit for limiting the energization of the horizontal magnet. This circuit is through the winding of relay 17 as traced. Upon the closure of this circuit the armature of relay 17 is attracted but this 40 relay being slow to operate does not close the circuit controlled by itself for a definite interval. At the end of this interval, relay 5 which is also a slow operating relay becomes 45 energized. Thus, through the operation of relays 17 and 5, the ground supplied at the 50 normal contacts of the armature of relay 5 is removed in a definite interval which is measured from the time when magnet 20 first becomes operated. 55 Upon the energization of magnets 12, 14 and 20, switching devices 21 and 22 become 60 operated so that the line of substation 1 is extended to trunk 23. Upon the establishment of this connection, a ground is extended 65 over the front contact and inner lower armature of magnet 14 to the third conductor of the line which leads to the cut-off relay 24 which, becoming energized, opens the circuit for line relay 2. This ground connection to the third conductor through the

agency of magnet 14 is only temporary and will remain there only until the ground is returned on the third conductor from the apparatus connected to trunk 23 in the ordinary and well known manner. 70

Upon the energization of relay 5, relays 6 and 10 become deenergized whereupon the magnets 12 and 14 immediately restore their armatures and by so doing remove the ground supplied for the energization of 75 magnet 20. However, by this time a ground is extended over the third conductor of the transfer circuit leading between switching devices 21 and 22 through the winding of relay 19 and thence through the two windings of magnet 20 in series, which is sufficient not only to energize relay 19 but to cause the continued energization of magnet 20. The energization of relay 5 also causes the deenergization of relays 3, 7 and 8 which 80 release. The locking circuit of relay 11 is also opened and this relay becomes deenergized but relay 13 becomes energized upon the deenergization of magnet 14 in a circuit from the third conductor of the trunk through the inner lower armature of magnet 14 at its back contact and the upper winding of relay 13 to battery and ground. 85

The lower winding of relay 13 is provided 90 so that if during the extension of a connection to another trunk, the circuit for the upper winding of relay 13 should become opened then this relay will remain energized through its lower winding and hence 95 in this way double connections are prevented. 100

At the end of the conversation the ground on the third conductor of trunk 23 is removed in the well known manner resulting 105 in the deenergization of relays 13, 19 and 24 and the deenergization of magnet 20 whereupon the apparatus concerned in this connection is wholly restored to normal. 110

What is claimed is:

1. In a telephone system, line magnets, link magnets, trunk magnets, a circuit for said link magnets controlled by said other magnets, and time controlling means for limiting the closing period of said circuit to a definite interval. 115

2. In a telephone system, line magnets, link magnets, trunk magnets, a circuit for said link magnets controlled by said other magnets, and another circuit controlled by said other magnets including relays slow to operate, said slow operating relays determining the closing period of said first circuit. 120

3. In a telephone system, lines, links and trunks, separately operable switching mechanisms for connecting said lines to said links, separately operable switching mechanisms for connecting said links to said trunks, line magnets, link magnets and trunk magnets cooperating to operate said 125 130

switching mechanisms to extend said lines through said links to said trunks, circuits for said link magnets controlled by said other magnets, and timing means for determining the length of the closing period of said circuit.

4. In a coordinate telephone system, line and trunk magnets for preparing a connection, link magnets for completing a prepared connection, circuits for said link magnets controlled by said other magnets, a timing device, and a circuit for said device controlled by said other magnets, said device having means for limiting the control exercised over said link magnets to a definite interval.

5. The combination in a telephone system

of a switch having a link for interconnecting incoming and outgoing lines, a magnet for said link, switch operating members, a circuit for said magnet, a timing relay, a circuit for said relay, both said circuits being closed by said switch operating members, means controlled by said relay upon its operation for opening the circuit of said magnet, and a source of energy for operating both the relay and the magnet, said relay adapted to measure an interval always greater than the interval required for the magnet to operate.

In witness whereof, I hereunto subscribe my name this 4th day of September A. D., 1923.

EDGAR H. CLARK.
